IMPACT WRENCH

Francis A. Jimerson, Athens, Pa., assignor to Ingersoll-Rand Company, New York, N. Y., a corporation of New Jersey

Application August 16, 1954, Serial No. 450,112

6 Claims. (Cl. 81—52.3)

This invention relates to impact tools, and more particularly to portable impact tools of the type having a motor driven hammer adapted to deliver to an anvil a constant turning force at low torque loads and at high torque loads, a series of high velocity rotary blows for rotating nuts, bolts or similar work pieces.

In tools of this type, and especially tools used in assembly line operations, it is highly desirable that the tool be simple in design and capable of operating relatively trouble free for long periods of time.

It is accordingly one object of this invention to provide an impact tool of relatively simple and compact design.

Further objects will become obvious from the following description and drawings in which:

Figure 1 is a vertical elevation, partly in section, showing a preferred embodiment of the invention.

Fig. 2 is a cross-sectional view taken through Fig. 1 along the line 2—2 looking in the direction of the arrows; and

Figs. 3 and 4 are similar to Fig. 2 but show different operative positions of the hammer relative to the anvil.

Referring to Fig. 1 of the drawings, a preferred form of the impact tool is shown as comprising, in general, a casing 8 housing a motor driven carrier 9 on which is eccentrically pivoted a hammer 10 having a longitudinal jaw, or lug, 16 arranged to strike a series of blows on a jaw 18 on an anvil 12 to rotate a workpiece 14.

The driving connection between the motor 15 and the carrier 9 includes a driver 28 positively connected to the motor 15 and bearing against a lever means 30 on the hammer 10 such that there is a lever, or camming force tending constantly to rotate the carrier 9 and hammer 10 about the anvil 12 and to rock the hammer 10 about its axis 20 out of engagement with the anvil 12. Thus the driver 28—lever 30 connection serves not only as a driver, but additionally as a means for disengaging the hammer 10 from the anvil 12 immediately after a hammer blow is struck so that the carrier 9 is free to be quickly accelerated to a high velocity prior to the hammer 10 striking the next blow. During this free movement of the carrier 9, the hammer 10 is positively rocked about its axis 20 into a position to engage the anvil by cam means 22, 24 on the hammer 10 and anvil 12, respectively.

Referring now in greater detail to the construction of the tool, the motor 15 is of the type, such as an air motor, that can be loaded until it stalls without damage to the motor. This type of motor is required because during every hammer cycle of the impacting portion of a tightening operation, the hammer 10, and hence the motor 15, is often brought to substantially a complete halt at the time of impact of the hammer 10 on the anvil 12, and then accelerated to maximum speed prior to the next blow.

Connected, as by splines 31, to the motor shaft 32 is the driver 28 which includes a pair of arms arranged to exert a driving and rocking force on the lever 30 integral with the hammer 10. The driver 28 shown is in the form

2

of a plate with a boss 29 for connection with the motor shaft 32 and has a pair of integral radially extending arms 34 and 36 forming a V-shaped area therebetween. The lever block 30 shown is roughly frusto-conical in cross-section and is located loosely with this V-shaped area with surfaces 38 and 40 arranged to be contacted by the arms 34 and 36, respectively. These surfaces are arranged, such that the contacted surface (e. g., surface 38 Fig. 2) is inclined with respect to the surface of the contacting driver arm (e. g., surface 41 Fig. 2). Inasmuch as the pivotal axis 20 of the hammer 10 is also the axis of the lever block 30, the force exerted by the driver 28 on the lever block 30 at this time not only tends to rotate the carrier 9, but also pivot the hammer 10 about the axis 20 to disengage the hammer 10 from the anvil 12. It is to be noted that the relative inclination between the lever and driver surfaces 38 and 41, respectively, is such that the hammer is pivoted in the same direction as the direction of rotation of the driver 28.

The magnitude of the disengaging force for any given motor torque is determined by the ratio of the lever arms E and F (see Fig. 3). The lever arm F is the distance from the driver axis to the contact point between the arm 34 and surface 38; the lever arm E is the perpendicular distance between the axis 20 and a line G perpendicular to line F and passing through said contact point. In this connection it is to be noted that at least a portion of the lever block surface 38 extends outwardly beyond the axis 20, or is radially more distant from the axis of the driver, and that the driver arm contacts this portion only of the lever 30. Thus the rotation force exerted along the line G lies at all times outside of the axis 20.

In addition to exerting a cam force tending to rock the hammer 10 about its axis 20, the driver 28 also drives, or rotates, the hammer about a more central axis—the axis 27 of the carrier. In furtherance to this end, the hammer 10 is mounted on and rotated with the carrier 9. The carrier 9 comprises a pair of end plates 52 and 54 rotatably mounted on the driver 28 and anvil stem 56, respectively, and a semi-circular connecting wall portion 58 having its center located approximately 180°, or diametrically opposite, from the transverse center of the relatively heavy jaw portion of the hammer 10 such that the wall serves additionally as a counterweight.

The hammer 10 which is roughly tubular in shape is eccentrically mounted on a pin 60 extending through the end plate 52 and 54. The bore 61 of the hammer shown has the same radius for approximately 250 degrees, the remaining arc 63 of 110 degrees is of a somewhat greater radius and with a different center point, thus a pair of longitudinal shoulders, or jaws, 16 and 62 are provided for engagement with the anvil jaws 18 and 64, respectively. The shape of the periphery of the bore arc portion 63 and, within relatively broad limits, the lengths of the arms are relatively unimportant from the tool operation standpoint, however, the jaws 16 and 64 are formed such that the striking jaw is substantially radial to the axis of the anvil 12 at the time of the blow (see Fig. 2). The depth of the jaws 16 and 62 is such that when the hammer is pivoted by the driver, the contacting hammer jaw moves clear of the contacted anvil jaw (see Fig. 3).

The anvil 12 is in the form of a cylinder with a recess 66 at the rearward end in which the motor shaft 32 is piloted, whereas the forward end, or stem portion 56 extends through the front end of the casing 8 and is adapted to fit a socket 68 or similar element for connection with a workpiece. Located along the rearward end portion of the anvil 12 and positioned within the hammer bore 61 is a radially extending lug 70 having a radius only slightly more than the radius of the 250° portion of the hammer bore 61 and being approximately 105° degrees

in length. This lug 70 provides the two shoulders, or anvil jaws, 18 and 64 the faces of which are substantially radial to the anvil axis so that when a hammer blow is struck the contacting surfaces—e. g., see jaws 16 and 18 in Figs. 2—are in parallelism and full surface contact is obtained. Of course these jaw surfaces may be inclined slightly from the radial to obtain a slight declutching or clutching effect where such effect is deemed desirable.

The outer periphery of the lug 70 serves additionally as the cam means 24 which cooperates with the cam means, or surfaces, 22 of the hammer bore 61 to rock the hammer about the pin 60 and place a hammer jaw in full alignment with an anvil jaw prior to a hammer blow. It is to be understood that although substantially circular cam surfaces are shown for the cams 30 and 24, such shape is not necessary to the operation of the tool. That is, a slightly eccentric shape may be used so long as there is relatively shockless mating of the cam surfaces 22 and 24 after release of the lever 30 (as occurs at approximately the hammer and anvil position shown in Fig. 4), and the hammer is pivoted into clutching position with the anvil—the position shown in Fig. 2—before the trailing edge of the hammer cam surface 22 leaves the anvil cam surface 24.

Reviewing briefly the operation of the impact tool and assuming the tool has been mounted on a workpiece, such as a nut 14 shown in Fig. 1, and assuming further that the hammer is rotated clockwise, as viewed in Fig. 2, the various elements of the tool will take the positions shown in Fig. 2 with the hammer shoulder 16 contacting the anvil shoulder 18 and the driver arm 34 contacting the lever surface 38. During any period when there is very little resistance to rotation of the anvil 12, as when the nut 14 is being threaded along the bolt 73 and prior to seating against a plate 74, the camming force exerted by the driver arm 34 and lever 30 tending to pivot the hammer out of engagement with the anvil is normally not sufficient to overcome the frictional force between the anvil and hammer jaws 18 and 16, respectively. Accordingly, the hammer 10 and anvil 12 will remain engaged so that the nut 14 is rotated constantly until the resistance to rotation increases above some predetermined value.

When the resistance to rotation of the anvil exceeds said predetermined value, the driver arm 34 acting on the lever 30 will rock the hammer about its axis 20 into the position shown in Fig. 3 with the hammer shoulder 16 moved out of alignment with the anvil shoulder 18. The motor 15 will then quickly accelerate the carrier 9 through 360 degrees such that the hammer is moving at substantially the maximum speed of rotation of the motor prior to striking the next hammer blow. During this relatively free rotation of the carrier 9, the hammer cam surface 22 comes in contact with the cam surface 24 (see Fig. 4) and the hammer is gradually and positively pivoted about its axis 20 against the pivotal force exerted by the driver arm 34 and lever 30 so that the hammer shoulder 16 is moved into alignment with the anvil shoulder 18 immediately prior to impact between these two shoulders.

The hammer striking a high velocity blow on the anvil, rotates the workpiece until, again, the pivotal force exerted by the arm 34 and lever 30 overcomes the frictional force between the hammer and anvil shoulders so that the hammer is rocked about its eccentric axis 20 and out of engagement with the anvil. It is to be understood that the time of disengagement of the hammer from the anvil will vary somewhat, depending upon the degree of tightness of the work. For example, when the work is relatively loose, the hammer will remain engaged with the anvil and rotate through several degrees prior to disengaging, whereas when the work is relatively tight there is a tendency for the hammer to rebound after a blow is struck, and the hammer will be disengaged from the anvil during such rebound.

The operation of the tool in the counterclockwise direction is identical with clockwise operation, except of course, impacting now occurs between the jaws 62 and 64 and the driving and declutching forces are exerted by arm 36 on surface 40.

While I have shown and described a specific form of my invention, it is to be understood that various changes and modifications may be made without departing from the spirit of the invention as set forth in the appended claims.

- 10 I claim:
1. A rotary impact tool comprising a motor, a rotatable carrier, an anvil, hammer element surrounding the anvil and pivotally mounted on the carrier on an axis eccentric to the carrier axis, clutch means on the hammer and anvil alternately engaged and disengaged during the impacting period of an operating cycle to rotate the anvil, cam means on the hammer and anvil arranged to contact during every hammer rotation to pivot positively the hammer about its eccentric axis to move said clutch means into engaging alignment immediately prior to contact therebetween, and a driving connection between motor and carrier for rotating the hammer and carrier about the carrier axis, said driving connection including a lever device constantly tending to pivot the hammer about its eccentric axis to disengage said clutch means.
  2. A rotary impact tool comprising a motor, a carrier, an anvil having a shoulder on its periphery, a hammer element pivotally mounted on the carrier on an eccentric axis and having a bore surrounding the anvil, said bore being shaped to provide a shoulder adapted to engage said anvil shoulder, cam means on the hammer and anvil arranged to contact during every hammer rotation to rotate positively the hammer about its eccentric axis to move the hammer shoulder into engaging alignment with the anvil shoulder immediately prior to contact therebetween, and a driving connection between the motor and the carrier for rotating the hammer and carrier about the carrier axis, said driving connection including a lever device constantly tending to pivot the hammer about its eccentric axis to move the hammer shoulder out of alignment with the anvil shoulder for disengaging the hammer from the anvil after contact between said shoulders.
  3. A rotary impact tool comprising a motor, a carrier, an anvil having a shoulder on the periphery thereof, a hammer element pivotally mounted on the carrier on an eccentric axis and having a bore surrounding the anvil, the surface of said bore being shaped to provide a shoulder adapted to engage said anvil shoulder and to provide a cam for engagement with the anvil shoulder during at least every 360 degrees of rotation of the hammer for pivoting the hammer about its eccentric axis to move the hammer shoulder into engaging alignment with the anvil shoulder immediately prior to contact therebetween, and a driving connection between the motor and the carrier for rotating the hammer and carrier about the carrier axis, said driving connection including a lever device constantly tending to pivot the hammer about its eccentric axis to move the hammer shoulder out of alignment with the anvil shoulder.
  4. A rotary impact tool comprising, a motor, a carrier, an anvil, a hammer element surrounding the anvil and movably mounted on the carrier, clutch means on the hammer and anvil engaged and disengaged alternately during the impacting period of an operating cycle to rotate the anvil, cam means on the hammer and anvil arranged to contact during every hammer rotation to rotate positively the hammer relative to the carrier to move said clutch means into engaged alignment immediately prior to contact therebetween, a driving connection between the motor and the carrier for rotating the hammer and carrier about the carrier axis, said driving connection including a lever on the hammer and an arm connected to and rotated by the motor and constantly bearing against the lever to exert a force tending to pivot the

hammer relative to the carrier to disengage said clutch means.

5. A rotary impact tool comprising, a motor, a carrier, an anvil, a hammer element surrounding the anvil and pivotally mounted on the carrier, clutch means on the hammer and anvil engaged and disengaged alternately during the impacting period of an operating cycle to rotate the anvil, cam means on the hammer and anvil arranged to contact during every hammer rotation to rotate positively the hammer relative to the carrier to move said clutch means into engaged alignment immediately prior to contacting therebetween, a driving connection between the motor and the carrier for rotating the hammer and carrier about the carrier axis, said driving connection including a surface on the hammer having at least a portion thereof extending outwardly beyond the hammer pivotal axis, and an arm connected to be rotated by the motor and constantly bearing against said portion of the hammer surface to exert a force tending to pivot the hammer about its pivotal axis to disengage the hammer from the anvil.

6. A rotary impact tool comprising a motor, a carrier including end plates and a connecting member, an anvil having a shoulder, a hammer element pivotally mounted on the carrier on an eccentric axis located approximately opposite the transverse center of said connecting member and having a bore surrounding the anvil, said hammer

element being somewhat enlarged at the portion adjacent the eccentric axis and the bore being shaped to provide a shoulder adapted to engage and disengage with the anvil shoulder during the impacting period of an operating cycle to rotate the anvil, cam means on the bore of the hammer for engagement with the anvil during at least every 360 degrees of rotation of the hammer to rotate positively the hammer about its eccentric axis to move the hammer shoulder into engaging alignment with the anvil shoulder immediately prior to contact therebetween, and a driving connection between the motor and the carrier for rotating the hammer and carrier about the carrier axis, said driving connection including a device constantly tending to pivot the hammer about its eccentric axis to disengage the hammer from the anvil.
